[57] CLAIM

The ornamental design for a toiletry case, as shown and described.

DESCRIPTION

FIG. 1 is a front perspective view of a toiletry case showing my new design;

FIG. 2 is a rear elevational view thereof;

FIG. 3 is a bottom plan view thereof;

FIG. 4 is a front perspective view, taken from the left side thereof, with the cover in a fully opened position and the inner panel and accessory racks thereof in a raised orientation;

FIG. 5 is a top plan view thereof with the cover fully opened and the inner panel and accessory racks thereof in a closed orientation;

FIG. 6 is a top plan view similar to FIG. 5 with the accessory supports shown in the raised position of FIG. 4;

FIG. 7 is a top plan view thereof with the cover, inner panel and accessory racks in the raised position of FIG. 4;

FIG. 8 is a rear elevational view thereof with the inner panel and support racks raised as in FIG. 7;

FIG. 9 is a left side elevational view thereof with the inner panel and support racks raised as in FIG. 7; and, FIG. 10 is an enlarged cross-sectional view taken along lines 10—10 of FIG. 6.

The broken line showing of toiletries in FIG. 4 is for illustrative purposes only and forms no part of the claimed design.
